BY ATTORNEY.

UNITED STATES PATENT OFFICE

166,862

COMBINED DOOR PULL AND LATCH FOR SLIDING DOORS

Robert D. Mason, Los Angeles, Calif., assignor to
Arcadia Metal Products, Inc., Arcadia, Calif., a
corporation of California

Application February 25, 1952, Serial No. 18,653

Term of patent 14 years

(Cl. D10—8)

To all whom it may concern:

Be it known that I, Robert D. Mason, a citizen of the United States, residing at Los Angeles, county of Los Angeles, and State of California, have invented a new, original and ornamental Design for a Combined Door Pull and Latch for Sliding Doors, of which the following is a specification, reference being had to the accompanying drawing forming part thereof.

Fig. 1 is a perspective view of a combined door pull and latch for sliding doors showing my new design.

Fig. 2 is a top plan view of Fig. 1.

Fig. 3 is a front view of Fig. 1.

I claim:

The ornamental design for a combined door pull and latch for sliding doors, substantially as shown.

ROBERT D. MASON.
